APPARATUS FOR TRANSFORMING CONTAINER BLANKS INTO CONICAL CONTAINER BODIES ABOUT A FORMING MANDREL AND AN IMPROVED FORMING MANDREL THEREFOR

Gunther Meyer-Jagenberg, Dusseldorf-Grafenberg, Germany, assignor to Jagenberg-Werke Akt.-Ges., Dusseldorf, Germany

Application December 6, 1955, Serial No. 551,427

Claims priority, application Germany December 9, 1954

11 Claims. (Cl. 93—36.1)

The present invention relates to the art of container manufacture.

More particularly, this invention relates to apparatus for forming a conical container of paper, cardboard or the like carton forming material.

Specifically, this invention relates to apparatus for manipulating a carton forming blank relative to a forming mandrel to provide a container body of general conical configuration having a square or rectangular cross section at the top and downwardly tapering sides merging into a rounded bottom. Containers of this character are described in U. S. Patent No. 1,915,027.

Thus the invention relates to improvements in apparatus for transforming container blanks into conical container bodies about a forming mandrel and an improved forming mandrel therefor.

In prior filed application Serial No. 511,686, in which the applicant is one of the joint inventors, there is disclosed an apparatus for assembling, impregnating and delivering containers. The arrangement of the present invention is an improved component of that general apparatus.

In the art of producing conical containers, particularly those intended to receive liquids such as milk or the like, the usual procedure includes positioning a container body blank, which has been cut in accordance with the desired finished shape of the container and has had binder applied in strips along one side of the blank and along the bottom edge so as to form the longitudinal container seam and applying this blank about a vertically positioned forming mandrel so that the two side edges of the blank overlap and form a longitudinal seam. The blank is applied against the mandrel with the bottom edge forming portion of the blank directed upwardly and extending above the top of the mandrel so that a dish-shaped bottom closure can be inserted in the open upper end of the body and connected thereto by folding, pressing and glueing. The finished container is then impregnated by dipping or spraying with paraffin or the like and after such action the wider upper part of the container body is provided with groove or score lines delimiting fold lines for a subsequently formed upper folded closure. If desired, the groove or score lines for the upper folding closure can be applied to the container body before the latter is impregnated.

In forming conical containers of the type in question the prior art and practice has employed a mandrel which consists of a truncated cone having its larger area at the base and four flat sides at the lower portion of the cone. Containers produced by these mandrels had the desired upper quadrangular cross section, narrowed toward their bottom, and the side walls merged into a round bottom. However, in the prior art arrangements the mandrel and thus the containers were only quadratic in the vicinity of the upper edge of the

2

initially formed container body, while below the upper edge thereof the mandrel and container in merging into a narrow circular bottom exhibited a corner structure that was of increasing roundness toward the bottom.

5 In other words, in that area of the container which subsequently had to be transformed into a folded closure there were present rounded corners.

Utilization of this known type mandrel revealed a deficiency in the fact that, in order to obtain an exact

10 and proper folding arrangement in forming the folded closure, the entire area of the body that is to be transformed into the closure should have clearly defined corner structures or, in other words, sharp edges. This is particularly true since the tool that has to produce the groove

15 or score lines, particularly what can be termed the counter punch, that is introduced into the container body during this grooving operation, has sharp edges. Utilizing such tools with container bodies having rounded corners in the area where the tools engage the wall structure

20 thereof unduly tensioned the wall structure of the container body which, due to the tendency of the material of which the container is made to resume its original form, prevented in most instances the proper formation of groove or fold lines and impaired the 25 foldability of the material so that the upper closure was not folded properly.

Accordingly, it is one object of the present invention to eliminate the foregoing deficiency in connection with

30 conical containers having a round bottom and a square or rectangular top by providing an improved container body forming arrangement which produces clearly defined and sharp edged corner structure in the upper area of the container body corresponding at least to that area down to the lower fold line for the folding closure so that 35 subsequent grooving and folding processes can occur satisfactorily.

It is a specific object of this invention to form a container body by applying a blank about a forming mandrel while subjecting the blank to heat.

40 In connection with this object, it is particularly advantageous to form the body with clearly defined sharp edged corner structures for a distance in excess of that quantity of the upper portion of the container body that is to be incorporated in the folded closure.

Specifically, therefore, it is an object of this invention to provide an improved forming mandrel having heating means associated therewith so that the container body formed thereon does not require any subsequent shaping,

50 has its final definitive form when laid about the mandrel, and all tensions that could occur in the material of the blank are eliminated under the action of heat so that the container body, after removal from the mandrel, retains the shape imparted to it by the shape of the mandrel. Thus, the present invention eliminates any tendency of 55 the container material to, in effect, spring back to original form.

Therefore, the invention comprehends a container body forming apparatus utilizing a heated forming mandrel 60 consisting of a body having a lower truncated pyramid form and an upper body portion continuing the small base area of the truncated pyramid, the upper body portion narrowing in the upward direction and merging into a circular end cross section. In connection with the mandrel, heating elements are embedded therein which are dimensioned in such a way as to produce a temperature assuring a permanent shape in the container body in correspondence to the shape of the mandrel.

It is a further object of the invention to provide the 65 mandrel with suction means in the area thereof adjacent the central median axis of the mandrel so that the edge of the blank first applied against the mandrel is held

securely on the mandrel until the overlapping edge having the binder thereon is applied into contact with the first-mentioned edge so that the longitudinal seam of the container is properly formed.

It is a further object to provide an improved mandrel structure which eliminates the drawback of transmitting heat from the heated mandrel to the mandrel supporting surface or plate, and in this connection the base surface of the mandrel is formed with cavities so as to have minimum surface contact with the supporting plate.

In connection with the satisfactory formation of container bodies from blanks, it is incumbent that the blank be correctly positioned relative to the mandrel before it is laid or folded thereabout. Positioning of blanks is a complicated operation in connection with modern machinery having a high rate of production, especially since such machines advance the blanks at a rather high rate of velocity by a suitable conveying arrangement usually incorporating grippers or tongs that individually feed or carry the blanks. It is readily seen that particular difficulties are encountered with the precise fixing of the opening intervals for any grippers that release the blanks and, further, the blanks are suddenly arrested in their forward motion when brought into the vicinity of the mandrel and in facing relation thereto. Additionally, the blanks may be improperly positioned since, in many instances the blanks are transmitted by intermediate conveying arrangements from the supply source or pile of blanks to the gripper mechanism which actually positions the blanks in front of the mandrel.

Accordingly, it is an object of this invention to provide an apparatus which, in association with an improved mandrel structure, manipulates successive blanks into the range of mandrels by feeding the blanks forward in the direction approximately parallel to the axis of the mandrel in an amount more than is necessary to arrange the leading edge of the blank adjacent the lower edge of the mandrel and then release the blank and subsequently impart movement to the blank in the opposite direction to position the blank in proper relationship relative to the mandrel. Specifically, it is an object of the invention to provide means independent of the blank feeding means for straightening the blank.

It is an additional object of this invention to provide a suction actuated blank supporting means adjacent the mandrel in spaced relation thereto to hold the blank while it is being straightened. In connection with the suction operated means the degree of vacuum applied thereby is such that the blank can be moved relative to the suction means during straightening and subsequently displaced from the suction means when it is laid about the mandrel.

Specifically, the invention has for an object to provide a blank straightening mechanism adjacent a forming mandrel and including the combination of transversely spaced blank supporting surfaces having suction openings therein, means for feeding a blank past said surfaces and operable to release the blank so that suction will hold the blank on the surfaces, and controlled straightening fingers extending transversely to the plane of the blank, mounted below the supporting means and movable toward the blank in unison for engaging the leading edge of the blank to straighten the blank relative to the mandrel regardless of the position of the blank at the moment of release.

Specifically, the foregoing objects further include a blank formation having a leading edge provided with a recess intermediate the side edges of the blank and an arrangement in which the straightening fingers are mounted for swinging movement in an upward direction so as to engage the leading edge of the blank, lift the same and straighten the same by simultaneous lifting and lateral displacement occasioned by the engagement of the finger means in the corners of the recess formed in the leading edge of the blank.

Further and more specific objects will be apparent from the following description taken in connection with the accompanying drawings, in which:

Figure 1 is a diagrammatic fragmentary side view partly in section and partly in elevation, illustrating the components of the apparatus which feed the blank relative to the mandrel, straighten the same, fold the same about the mandrel, and press it thereagainst.

Figure 2 is a diagrammatic top view of the parts shown in Figure 1 with the initial blank conveyor eliminated,

Figures 3 to 7 are respective diagrammatic views illustrating individual and successive stages in the operation of applying the blank about the mandrel, these figures illustrating the relative positions of the folding and pressing tools during the several stages,

Figures 8 to 10 are various views illustrating the improved mandrel,

Figure 11 is a view partly in longitudinal section and partly in elevation, illustrating the mandrel having a container body formed thereon and the bottom closure inserted therein,

Figure 12 is a cross sectional view taken along the lines 12—12 of Figure 11,

Figure 13 is a fragmentary front elevational view illustrating the means for straightening the blank,

Figure 14 is a view similar to Figure 13 but illustrating the straightening means in the position immediately before the blank is laid about the mandrel.

Bearing in mind that the plant installation disclosed in prior application Serial No. 511,686 incorporates a container body forming station which includes a rotary turntable carrying a plurality of forming mandrels that is indexed step by step past a mechanism for applying blanks about the successive forming mandrels, the present invention will be described only with reference to a single mandrel and the mechanism for applying the blank thereabout.

As illustrated in Figure 1, the blanks 1 to be shaped into the conical container are fed from a stack or pile arrangement, not shown, by a continuously circulating conveyor chain arrangement denoted diagrammatically at 3. The conveyor chain arrangement includes gripper means or grabs 2. The conveyor in the range of the place of delivery of the blanks passes about guiding wheels 4 and 5. In the position illustrated in Figure 1, the blanks are delivered to a feeding mechanism, including spaced levers 7 mounted for movement about a shaft 6. The front end of each lever is provided with tongs or gripper means 8 which engage the side edges of the blank above the leading edge thereof. The up and down movement of the levers 7 is effected by a pair of crank wheels 9, the slides 10 of which are engaged in guide slots 11 formed in the levers. Thus, rotation of the crank wheels rocks the pair of levers up and down. In the upper position the tongs 8 engage the side edges of the blank. The levers then move downwardly to bring the blanks in front of the forming mandrel 12 mounted on the base plate or turntable 36. During the downward feeding movement of the levers 7 the blank engaged by the tongs 8 is fed downwardly a distance further than that which would otherwise be necessary to correctly position the blank in facing relation to the mandrel 12. Then the blank is released by opening the tongs 8 and the levers are swung upwardly back to starting position ready to engage the next successive blank. When the blank is gripped and released the opening and closing of tongs 8 is effected by levers 8a which in the upper and lower position of pivoting levers 7 come into contact with fixed cams 8b. In a similar way the opening of grabs 2 at the moment of delivering the blank is effected by means not shown.

As shown in Figure 2, blank supporting means are arranged in transversely spaced relationship in front of and on opposite sides of the mandrel. These supporting means are constituted by what can be termed fixed suction

ledges 13 having suction openings therein on the side facing the mandrel, so that when the blank is fed downwardly, as shown in Figures 1 and 13, it is moved across the face of the suction ledges so that when released by the tongs or grippers 8 the blank is held against the ledges by the suction. The leading edge of the blank 14 when released by the grippers or tongs 8 is below the lower edge 12^c of the quadrangular part of the mandrel.

As shown in Figure 13, the trailing edge of the blank is below the top of the mandrel. Thus, the initial release of the blank purposely leaves it in an incorrect position. Below the leading edge of the blank in its released position are mounted the straightening means consisting of a pair of movable straightening fingers 15 extending transversely of the plane of the blank toward the mandrel and having a length such as to cross the path of movement of the blank. These straightening fingers are mounted by means of clamping bolts 16 and slots 17 on levers 18 mounted to oscillate about fixed pivots 19. Due to the clamping bolt and slot arrangement the straightening fingers are adjustably mounted relative to the levers 18. The free ends of the rocking or oscillating levers 18 are provided with guide holes 20 engaged in slots 21 of a vertically movable control member 22. The control member 22, as shown in Figure 1, is carried on one arm 24 of a double-armed lever pivotally mounted about pivot pin 23. The other arm 23' of the lever carries a roller 25 bearing against the periphery of a cam 26. Thus, rotation of cam 26 oscillates the double-armed lever arrangement to move the straightening fingers.

During upward movement of the control member 22 from the position shown in Figure 13 to that shown in Figure 14, the straightening fingers 15 move in arcs of a circle about fixed pivots 19 and in so doing lift the blank 1 until it has reached its proper height relationship relative to the mandrel. Simultaneously, with the lifting movement there occurs a straightening action with respect to the lateral position of the blank 1 since the straightening fingers 15 in addition to their upward component of movement have a lateral outward component of movement wherein they engage in the corners of a recess 27 formed in the leading edge 14 of the blank. As previously indicated, the degree of suction exerted in the openings of the suction ledges 13 is sufficient to hold the blank on the ledges but permit it being straightened by the movement of the fingers 15 relative to the fixed suction ledges 13.

The now straightened blank is in the position shown in Figure 14; that is, it is in proper relationship relative to the forming mandrel 12. The forming mandrel 12, about which the blank is to be folded into tube form and joined into a container body, is more clearly shown in Figures 8 to 10. As disclosed, the forming mandrel consists of a body having a lower portion in the shape of a truncated pyramid 12^a and an upper portion 12^b continuing the small base area of the pyramid and which, starting from that small base area, that is, approximately at the dotted line 12^d, narrows upwardly and changes into a circular or rounded end. The lower portion of the forming mandrel below the edge 12^c is reduced and supported in what can be termed a pedestal 27 which, as shown in Figure 11, extends laterally of the mandrel and forms a bearing structure, as at 28, for supporting pivot pins carrying connecting rods 30 which, in turn, are connected to and carry a movable pressing member 29, Figure 1. This pressing member 29 applies the end 62 of the blank over the end 61 in the formation of the longitudinal seam, as shown in Figures 3 to 7. The pressing member 29 is actuated by toggle lever 31 pivotally supported in supporting member 33. One end of the toggle lever 31 is connected through an elastic draw bar means 32 with one of the connecting rods 30, while the other end of the toggle lever has a roller 34 mounted thereon engaging in a cam track 35 which controls the to

and fro movements of the pressing member 29. The pedestal 27 at the bottom of the heated mandrel 12 is fastened to the machine plate or base 36 and in order to avoid undue heat radiation, that is, undesirable transmission of heat to the base plate, only small annular contact surfaces 38, in the range of fastening apertures 37, engage the top of the plate 36. Thus, in effect, the mandrel proper is elevated above the base plate, leaving an air space between the mandrel and the base plate.

As previously indicated, the mandrel is heated so that in the range of the container body that is to form the upper closure there be sharply defined corner structures as determined by the lower portion 12^a of the mandrel. As shown in Figures 11 and 12, heating elements 49 are embedded in the mandrel. These heating elements, in addition to facilitating the formation of sharply defined corner structures on the container body, likewise impart heat to binder materials to make them adhesive. When the binders are of a thermoplastic nature or if other adhesives are used, the heating elements accelerate the escape of solvent and thereby effect a rapid setting of the adhesive. Thus, the application of heat to the mandrel has a two-fold purpose, to facilitate the formation of the corner structures, and to activate and/or accelerate the adhesive bonding in the formation of the longitudinal seam for the container body.

In order to support the opposite side edges of the blank when they are folded about the mandrel, the latter is provided, in the area thereof coinciding with the longitudinal seam, with a row of suction openings 50 which communicate with a vertical channel 51 extending longitudinally of the mandrel. This vertical channel 51 is via a hose or conduit means, not shown, connected with suitable evacuation apparatus.

On the side of the mandrel opposite the pressing member 29 are mounted the mechanisms for applying the blank to and about the forming mandrel. These mechanisms or tools are moved to and fro in harmony or synchronism with the movement of the other components of the apparatus and are carried by a carriage 39. The carriage 39 is mounted on a slide 40 for movement toward and away from the mandrel. The carriage is actuated by a draw bar 41 engaging at the free end of a cam actuated lever 42. The lever 42 mounts a roll 43 engaged in a cam track in a cam 44. Thus, rotation of the cam oscillates lever 42 about pivot 42^a and imparts reciprocatory movement through draw bar 41 to carriage 39 and the tools carried thereby.

50 A pressing member or clamping ledge 45 is provided with a bolt means extending from its rear face, including the bolt 46. The bolt means are passed through apertures in the upright arm 39^a on the carriage 39. A spring 47 surrounds bolt 46 and bears between the rear face of the pressing member 45 and the front face of the rear leg or upright 39^b of the carriage. This spring arrangement assures an elastic application of the pressing member 45 against the mandrel 12. On either side of the pressing member 45 are fold forming ledges 48 which are fastened to the carriage 39. These fold forming ledges 48, as shown in Figures 3 to 5, press the side of the blank about the sides of the mandrel in U-shape formation. Thus, in operation, the forward movement of carriage 39 causes the pressing member 45 to engage the rear face of the blank, displace it from the suction means 13, and apply it against the mandrel. The continued movement of the carriage causes the fold forming ledges 48 to engage the blank on opposite sides of the mandrel and press the blank about the same in U-shaped formation, as shown in Figure 4.

The overlapping of the lateral edges of the blank 61, 62, respectively, is effected by angle-shaped folding members 52A, 52B, respectively. Each of these angle-shaped folding members are carried by levers 53. The levers

53 are pivoted about pins 54 and include an end structure extending beyond the pins formed into two segments 55 which are engaged by oscillatable gear wheels 56 suitably driven to effect oscillation of the levers 53 and the folding angles.

Above the mandrel 12 is disposed a mechanism for inserting the dish-shaped bottom closure 57 into the container body. Each dish-shaped bottom closure 57 is inserted into the round smaller end of the container body with its flanges directed outwardly. The edges of the container body extend above the flanges so that subsequently the edges of the container body can be folded over the flanges to firmly adhere the bottom to the body. This operation is performed at a subsequent station in the machine. The bottom blanks or closures 57 are fed forward along a guide path 58 into the range of movement of a vertically reciprocable pressing head or punch 60 which is actuated by a toothed segment 59, the punch inserting the bottom closure 57 into the upper end of the container body, as clearly shown in Figure 11.

Figures 3 to 7 diagrammatically disclose the sequence of operation. Starting from the position shown in Figure 3, in which the blank has been straightened relative to the mandrel, as in Figure 14, the carriage 39 is moved toward the mandrel a distance sufficient to engage the face of the blank remote from the mandrel and press it against the same. Simultaneously, through the forward movement of the carriage, the folding ledges 48 engage the side portions of the blank adjacent the sides of the mandrel and fold the blank about the mandrel in U-shape, as in Figure 4. Then, as shown in Figure 5, the lever 53 carrying folding angle 52^a oscillates in advance of the other lever and engages that portion or end 61 of the blank that is to form the interior layer of the longitudinal seam and applies it against the side of the mandrel. Simultaneously, suction is exerted through openings 50 to hold the end 61 of the blank against the mandrel so that the fold angle 52^a can start to move back from the mandrel, while fold angle 52^b is moved toward the same to apply end 62 of the blank in overlapping relation over the previously applied end 61. As the levers 53 start to withdraw, the presser element 29, which is moving toward the mandrel, engages the overlapped ends of the blank and presses the same against the mandrel so that the adhesive which is embodied on the side edge of the blank can be activated to form the longitudinal seam and transform the blank into a container body.

After the afore-described operations have been completed and a container body is formed, the dish-shaped closure part is inserted into the container body to the position shown in Figure 11, following which the mandrel is moved to the next station wherein the upper portion of the container body is folded over and connected with the closure.

What is claimed is:

1. In the formation of tubular container bodies by folding a blank about a forming mandrel and subsequently uniting opposite lateral ends of the blank by a longitudinal seam structure, the improvement comprising feeding a blank in spaced relation to and in a direction approximately parallel to the mandrel a distance in excess of that necessary to dispose the blank in a position where it is in proper coincidence with the mandrel, releasing the blank, supporting the blank in its released position, and then prior to folding lifting the supported blank while straightening the same relative to the mandrel to coincide the axis of and leading edge of the blank with the mandrel.

2. In the formation of tubular container bodies by folding a blank about a forming mandrel and subsequently uniting opposite lateral ends of the blank by a longitudinal seam structure, the improvement comprising feeding a blank in spaced relation to and in a direction approximately parallel to the mandrel a distance in excess of that necessary to dispose the blank in a position where

it is in proper coincidence with the mandrel, releasing the blank, supporting the blank in its released position by suction, and then prior to folding lifting the supported blank while straightening the same relative to the mandrel to coincide the axis of and leading edge of the blank with the mandrel.

3. A forming mandrel for container forming machines for producing conical containers of paper, cardboard or like carton-forming material having a quadrangular upper cross-section tapering downwardly and merging into a round bottom, said mandrel having a quadrangular end and a round end and comprising a body including an upper container body forming portion shaped as a truncated pyramid and continuing from the base of the pyramid a remainder container body forming portion convergently shaped and merging into the round end, heating means associated with the mandrel body for facilitating the formation of sharply defined corner structures by the truncated pyramid shaped portion whereby the subsequent formation of a folded closure out of the material of the body in the upper portion thereof is facilitated, one end of the mandrel constituting a base, supporting means for the base and said base having excavations therein to reduce surface contact with the supporting means to thereby minimize heat transmission between the heated mandrel and the supporting means.

4. In apparatus for forming conical containers about a shaped forming mandrel, means for feeding a blank at laterally spaced relation to and along side the mandrel a distance further than that necessary to properly coincide the blank with the mandrel, said feeding means including means operative to release the blank, means for supporting the blank in its initially released position and operative to permit movement of the blank relative to the mandrel while in supported position and movable straightening means mounted for movement in a direction opposite to the feeding movement of the blank and cooperable with the leading edge thereof for straightening the blank relative to the mandrel.

5. Apparatus as claimed in claim 4 in which the means for supporting the blank comprise suction operative means.

6. Apparatus as claimed in claim 5 in which the suction operative means comprise transversely spaced apertured supporting members with the apertures being directed toward the mandrel and said members being disposed on opposite sides of the axis of the mandrel.

7. Apparatus as claimed in claim 4 in which the means for feeding the blank comprise swinging lever means movable in an arc adjacent to the mandrel and the means for supporting the blank comprise supporting bodies having arcuate surfaces approximately coinciding with the arc of movement of the blank in its feeding movement and said surfaces having suction apertures therein facing the mandrel.

8. Apparatus as claimed in claim 4 in which the movable straightening means comprise control straightening fingers extending transversely of the plane of the blank, mounted below supporting means and movable toward the blank in unison for engaging the leading edge of the blank to straighten the same relative to the mandrel regardless of the position of the blank at the moment of release.

9. Apparatus as claimed in claim 8 in which the leading edge of the blank has a recess therein intermediate its opposite side edges, said apparatus further comprising swingable means supporting said straightening fingers, transversely spaced fixed pivots supported said swingable means, and control means for the swingable means operable to swing said straightening fingers upwardly and outwardly in engagement with the leading edge of the blank whereby simultaneous movement of the straightening fingers in engaging them in the recess effect simultaneous lifting and lateral displacement of the blank relative to the mandrel and coincides the blank with the mandrel.

10. Apparatus as claimed in claim 9 and further including means mounted on the side of the supporting means remote from the mandrel and movable toward the mandrel to remove the blank from the supporting means and fold the same about the mandrel.

11. Apparatus as claimed in claim 10 in which said mandrel has suction openings therein on the side opposite the supporting means, said apparatus further including means operative to engage the free ends of the blank after they have been folded in parallelism to apply them in overlapping relation against said side of the mandrel, said

5

last mentioned means applying one edge over the suction openings whereby the blank is securely held during overlapping of the other edge.
